[57] CLAIM

The ornamental design for an escutcheon for plumbing fitting, as shown and described.

DESCRIPTION

FIG. 1 is a top perspective view of an escutcheon for plumbing fitting showing our new design;

FIG. 2 is a side elevational view thereof, the other sides being the same as the side shown;

FIG. 3 is a top plan view thereof;

FIG. 4 is a bottom plan view thereof;

FIG. 5 is a cross-sectional view taken on line 5—5 of FIG. 3; and,

FIG. 6 is a cross-sectional view taken on line 6—6 of FIG. 3.

FIG. 1

FIG. 2

FIG. 5

FIG. 6

FIG. 3

FIG. 4
